TONE CONVERTER

James L. Finch, East Rockaway, N. Y., assignor to
 Radio Corporation of America, a corporation of
 Delaware

Application February 22, 1943, Serial No. 476,787

6 Claims. (Cl. 178—66)

1

The present invention relates to a signaling means wherein intelligence is transmitted according to keyed alternating current energy, and relates, more particularly, to a converter for such systems wherein keyed alternating current of one frequency is utilized to key alternating current of another frequency.

An object of the present invention is to improve the operation of tone signal converters.

A further object of the present invention is the provision of a signal converter which has a minimum effect on the shape of the signal operated upon.

Still another object of the present invention is the provision of a tone converter in which the amplitude of the output signals is of substantially a constant "weight" in spite of variations in incoming tone level. "Weight" is the measure of length of actual marking intervals with relation to the length of balanced characters, that is, those in which marking and spacing intervals are equal.

A further object of the present invention is the provision of a high speed signal converter which is operable without difficult adjustments on different types of radio transmitters.

In accordance with the principles of the present invention alternating current wave energy, which is keyed according to signal characteristics to be transmitted, is amplified, then rectified, then limited to a uniform amplitude, any remaining tone frequency components are removed and the resultant pure signal applied to a stable and rapid acting amplifier system which controls a utilization circuit such as a radio transmitter.

The novel features which, it is believed, are characteristic of the present invention are pointed out with particularity in the appended claims. The invention will, however, be more completely understood by reference to the following detailed description which is accompanied by a drawing wherein transformer 1 has a primary and a secondary winding, across the primary of which a telegraph modulated tone signal is applied. Across the secondary winding of transformer 1 is connected a variable level control 2 to compensate for variations in the level of signals applied to the input winding of the transformer. To the moving contact on the level control 2 is connected the control electrode of amplifier tube 3. Amplifier tube 3 is shown in the drawing as being of the pentode type. Obviously, any other type of amplifier tube may be used if desired. The connections of the electrode of the amplifier tube 3 are purely conventional

2

and, hence, will not be described in any further detail. The use of one stage of audio frequency amplification for the received tone signal reduces the input signal requirements to a level which will always be available at a transmitting station in spite of variations in line transmission characteristics.

I have found that it is undesirable to use more than one stage of amplification because the increased sensitivity would then increase the susceptibility of the converter to stray energy pickup of various kinds existing at a transmitting station.

The primary of transformer 5 is shunt coupled 15 to the output circuit of amplifier tube 3. The secondary winding of transformer 5 is center tapped and has connected across its outer terminals a full wave rectifier 6, preferably of the dry contact type or copper oxide disc type. It 20 will be noted that the center tap of the secondary winding of transformer 5 is not connected directly to ground but is connected to an adjustable point on resistor 8. Resistor 8 constitutes, with resistors 4 and 7, a potential divider 25 across the source of anode power supply 26. Thus a variable bias may be applied to the rectifier of such amplitude that audio signals or noise below a certain level are not rectified and does not affect the following portions of the circuit. 30 The output of rectifier 6 is connected to a resistor 13 constituting the input circuit of a limiter tube 9. Limiter tube 9 is operated at substantially no bias and at a low-plate potential determined by the position of tap 19 on resistor 7. The plate 35 potential is so determined that for increases of signal input level above a predetermined value no further corresponding increase in plate current of tube 9 is obtained. Therefore, though the output level of the rectified signals from 40 rectifier 6 may vary considerably, the signal level in the output circuit of tube 9 is substantially constant. Typical signal input values across resistor 13 may vary between —25 volts for marking intervals to zero volts for spacing intervals. 45 Since the signal appearing in the output circuit of tube 9 may contain some of the tone signal components from the input, a filter circuit 10, including a series inductance 11 and a pair of shunt capacities 12, is provided in the plate circuit. The filter circuit 10 is so constituted as to 50 reject the tone components of the signal. Thus the signal appearing across resistor 20 constituting the input circuit of control tube 15 is substantially a pure square wave varying abruptly between the zero potential condition of spacing to

the full potential condition of the marking impulses of the signal wave. The anode of control tube 15 is connected to an interior source of anode potential labeled +15V through a fairly high resistance 17 so arranged that as the tone input to the converter varies in accordance with the marking and spacing intervals, the potential on the plate of the control tube varies from a mark value of -180 volts to a space potential of zero volts. This voltage appears directly on the grids of keying tubes 24 of the radio transmitter (not shown). Keying tubes 24 may be so arranged in the transmitter circuit that when the marking potential of -180 volts is applied to their grids substantially no current is drawn by tubes 24 and all of the energy of the plate supply is applied to the transmitter. During spacing intervals when substantially zero potential is applied to the grids of tubes 24, the current drawn by these tubes is sufficient to prevent the application of plate potential to the operative portions of the transmitter. This method of keying is well known in the art and does not constitute a part of the present invention. It will, therefore, not be more fully described here.

It should be noted that the entire circuit as so far described is, with the exception of the keyer tubes 24, contained within a grounded metallic shield denoted by reference character 25. The required anode potentials for the tubes of the converter are supplied by an anode power supply 26 also contained within the shield 25 to avoid interference pick-up. For the same reason input transformer 1 preferably is electrostatically shielded as indicated in the drawing. Because of the potential requirements of the output circuit of the converter, the positive terminal of the anode power supply is grounded and connected to the shield 25, while the negative end of the anode power supply is at high potential with respect to the shield.

It should be particularly noted that the placing of the limiter tube 9 ahead of filter 10 causes any variation in level of the signal applied to the filter 10 to be of negligible proportions, even for a relatively large variation in audio input. This is desirable for the reason that if the rectified signal is applied directly to the filter the filter tends to change the length of the characters, that is, the proportions of the marking and spacing intervals of the signal wave due to the filter causing a rounding off of ends of the signal impulses with variations in input level. If the ends of the signals are rounded off and the level varies, as the clipping level of the limiter is constant, the stronger the incoming tone signals are, the greater is the length of the marking characters applied to the central tubes. However, by placing the filter after the limiting tube, in accordance with the present invention, so as to make the input to the filter as nearly constant amplitude as practical, despite variations in the incoming tone level, the envelope of the intelligence characters is maintained with a substantially square wave shape, assuming that the incoming tone signal envelopes are square and have not been rounded by control line filters.

Furthermore, it is contemplated that the filter 10 be arranged as a low pass filter having a cut-off so arranged as to provide a maximum attenuation for the second harmonic of the input tone frequency and preferably this attenuation should at all times not be less than 30 db. in order that maximum possible keying speeds may be obtained. For facsimile transmission a frequency

stop filter tuned to reject the tone frequency may be used. The filter is designed to be readily replaceable to take care of changes in tone frequency. I have found that it is not desirable to use a resistance-condenser or time constant type of filter which is useable over a wide frequency range because that type does not attenuate the rectified ripple frequency sufficiently without introducing excessive attenuation of the desired signal components. Unless the rectified ripple frequency is very greatly attenuated it may be found that at the threshold point of the keying tubes 20 the ripple frequency may key the transmitter. This, of course, would introduce a great deal of distortion into the transmitted signal but is overcome by using a sharp cutting filter, such as the present filter 10.

While I have illustrated a particular embodiment of the present invention, it should be clearly understood that it is not limited thereto since many modifications may be made in the several elements employed and in their arrangement and it is, therefore, contemplated by the appended claims to cover any such modifications as fall within the spirit and scope of the invention.

I claim:

1. A signal converter including an input circuit for a keyed tone signal, means for amplifying said tone signal, means for rectifying said signal, means for so biasing said rectifying means that it is unaffected by input signals below a predetermined value, means for limiting said rectified signals to a predetermined level and means following said limiting means for removing tone components from said rectified and limited signals.

2. A signal converter including an input circuit for a keyed tone signal, means for rectifying said signal, means for so biasing said rectifying means that it is unaffected by input signals below a predetermined value, means for limiting said rectified signals to a predetermined level and means following said limiting means for removing tone components from said rectified and limited signals.

3. A signal converter including an input circuit for a keyed tone signal, means for rectifying said signal, means for so biasing said rectifying means that it is unaffected by input signals below a predetermined value, means for limiting said rectified signals to a predetermined level and means following said limiting means for removing tone components from said rectified and limited signals, said last mentioned means including a rejection filter tuned to the frequency of said tone.

4. A signal converter including an input circuit for a keyed tone signal, means for rectifying said signal, means for so biasing said rectifying means that it is unaffected by input signals below a predetermined value, means for limiting said rectified signals to a predetermined level and means following said limiting means for removing tone components from said rectified and limited signals, said last mentioned means including a rejection filter tuned to the frequency of said tone and a utilization circuit coupled to the output of said filter.

5. The method of transferring intelligence signals from one carrier to another which includes the steps of rectifying the first carrier of said signals, limiting the rectified signals to a predetermined level to remove variations in signal level, removing components of said first carrier from said rectified and limited signals and utilizing the remainder to key said other carrier.

6. A signal converter including an input circuit for a carrier wave carrying intelligence signals, means for rectifying said carrier to obtain said signals, means for limiting said rectified signals to a predetermined level, and means following said limiting means for removing carrier components from said rectified and limited signals, said

last mentioned means including a rejection filter tuned to the frequency of said carrier and a utilization circuit coupled to the output of said filter, said utilization circuit including a keying tube for modulating a second carrier by said signals.
